UNITED STATES PATENT OFFICE.

CHARLES D. CARTER, OF NEW YORK, N. Y.

COMBINED COAL AND GAS STOVE.

1,315,008.

Specification of Letters Patent. Patented Sept. 2, 1919.

Application filed March 20, 1918. Serial No. 223,532.

To all whom it may concern:

Be it known that I, CHARLES D. CARTER, a citizen of the United States, residing in the city and county of New York, State of New York, have invented a new and useful Combined Coal and Gas Stove, of which the following is a specification.

It has heretofore been proposed to provide a stove or cooking range with a single oven which could be heated by fuel of either a solid or a fluid nature. Considerable difficulty has, however, arisen in a stove of this type in obtaining the same efficiency with one type of fuel as with the other, since if a maximum efficiency is obtained with solid fuel, such as coal, the same efficiency cannot be obtained when employing gas as a fuel. The same holds true if the construction is such that a maximum efficiency is obtained with gas since the same efficiency has not been obtained when coal is used as a fuel.

It is the primary object of my present invention to devise a novel construction of a stove which will give the same efficiency with a solid fuel as it will with a fluid fuel.

In accordance with my present invention, the oven bottom is provided with an opening which when the stove is used with coal is covered by a conventional construction of a cover. When the stove is to be used with gas, such cover is removed and the flames from a burner located beneath the opening pass through such opening and operate with a novel construction and arrangement of a combined baffle and grid which is removable as a unit from the oven and is used only when fuel of a fluid nature is employed.

My invention further consists of a novel construction of a combined baffle and grid.

A further purpose of my invention is to devise a novel construction and arrangement of a stove having a single oven adapted to be heated by coal or gas and wherein when gas is employed as a fuel, all of the operations which can be carried out in connection with a regular gas range can be employed, such as for example, baking, roasting, and broiling.

Other novel features of construction and advantage will hereinafter more clearly appear in the detailed description of my invention.

For the purpose of illustrating my inven-

tion, I have shown in the accompanying drawings a typical embodiment of it which is at present preferred by me, since this embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in sectional elevation, a combined coal and gas stove embodying my invention, the section being taken on line 1—1 of Fig. 2.

Fig. 2 represents a section on line 2—2 of Fig. 1.

Fig. 3 represents a sectional view of a portion of a stove, showing the opening in the bottom of the oven with a cover which closes such opening when solid fuel is used.

Fig. 4 represents a top plan view of the combined baffle and grid employed.

Fig. 5 represents a bottom plan view of the construction seen in Fig. 4.

Fig. 6 represents a section on line 6—6 of Fig. 4.

Similar numerals of reference indicate corresponding parts.

Referring to the drawings:

1 designates a combined gas and coal stove embodying my invention and since certain parts of the construction are old *per se*, I have deemed it unnecessary to illustrate and describe in detail the complete stove. The stove is provided with a firepot 2 which is adapted to receive the solid fuel, such as for example, coal, wood, or their equivalents, and which communicates with a flue 3 which passes around an oven 4 and into the smoke-pipe 5 in the usual manner, the flue being provided with a damper controlled port 6 in the usual manner. The bottom 7 of the oven is provided with an opening 8 which is surrounded by a depressed seat 9 adapted to receive a cover 10, which when the stove is to be used for solid fuel is in the position seen in Fig. 3 and closes the opening 8. The seat 9 is provided with a desired number of apertures 11 which insure the proper ventilation of the oven when gas is employed as a fuel. The opening 8 forms a communication with a burner chamber 12,

the casing 13 of which is disposed in the laterally extending bottom portion of the flue 3.

14 designates a burner to which the fluid fuel is conducted in any desired or conventional manner. 15 designates a combined baffle and grid which consists of a metal plate or disk 16 which is provided with a grating or grid formed by the radially projecting arms 17. The plate has depending therefrom the legs or standards 18, three of which are preferably employed. The side standards 18 are slotted near their top to form guides for a baffle 19 which consists of a rectangular shaped frame, the sides of which are recessed on their bottom face so as to receive the plates 20 and 21 and between these plates is preferably disposed a layer of heat resisting material, such as for example, asbestos 22. The sheets 20 and 21 and the sheet of asbestos 22 are secured to the baffle 19 by means of fastening devices 23, such as for example, rivets. The sides of the baffle 19 near the rearward end of the baffle are provided with the plates or shoes 24. The plate or disk 16 is provided with a grasping handle 25 which has a longitudinally extending slot 26 into which extends an upwardly projecting lug 27 connected to or integral with the baffle 19. 28 designates a grasping handle which is secured to the baffle 19 by means of a fastening device 29. The stove is also provided with a burner chamber 30 having at its upper end the grating 31 and provided with burners 32.

33 is an exhaust flue communicating with the smoke pipe 5.

In the operation of the stove, assuming that it is desired to employ a solid fuel, such as coal, the combined baffle and grid 15 is removed from the oven and the cover 10 is placed in the position seen in Fig. 3 to cover the opening 8 and also the ventilating apertures 11. When it is desired to use fuel of a fluid nature, such as for example, gas, the combined baffle and grid is employed, the cover 10 being first removed. The combined baffle and grid 15 is placed on the oven bottom with its forward post engaging the stop 34. If it is desired to bake, the baffle 19 is in its forward position seen in Figs. 1 and 4. If it is desired to broil or cook, for example to boil, the user takes hold of the grasping handle 28 and slides the baffle 19 rearwardly into the position seen in Fig. 2.

It will thus be seen that in accordance with my present invention, when the stove is used with gas, anything can be cooked in the oven in a similar manner to that in which the cooking can be effected on a gas range. The combined baffle and grid can also be placed on top of a stove or above

the gas burner 32 when it is desired to cook 65 anything with a slow heat, as is evident.

It will be seen that when the stove is used as a coal range, the combined baffle and grid 15 is removed from the oven so that the entire space of the oven is available for cooking 70 purposes.

It will now be apparent that I have devised a novel and useful combined coal and gas stove, which embodies the features of advantage enumerated as desirable in the 75 statement of the invention and the above description, and while I have, in the present instance, shown and described a typical embodiment of it which will give in practice satisfactory and reliable results, it is 80 to be understood that this embodiment is susceptible of modification in various particulars without departing from the spirit or scope of the invention or sacrificing any of its advantages. 85

Having thus described my invention, what I claim as new and desire to secure by Letters Patent, is:—

1. In a stove of the character described, an oven chamber, a burner chamber having 90 means of communication with the lower portion of the oven chamber, a burner within the burner chamber, a grid arranged above the burner chamber and having supporting legs, a baffle arranged upon one side of the 95 grid and having slidable connection therewith, a substantially horizontal handle carried by the grid and having a longitudinal slot, an element secured to the baffle and operating within the longitudinal slot, and a 100 second handle arranged above and near the first named handle and carried by said element.

2. In a stove of the character described, an oven chamber, a burner chamber having 105 communication with the lower portion of the oven chamber, a burner within the burner chamber, an open grid arranged above the burner chamber and having supporting legs, the side legs of the grid having 110 recesses formed therein, and a baffle arranged beneath the grid and slidable within the recesses of the legs and adapted to cover the opening of said grid.

3. In a stove of the character described, 115 an oven chamber, a burner chamber having means of communication with the lower portion of the oven chamber, a burner within the burner chamber, a grid arranged above the burner chamber and having supporting 120 legs, the side legs of the grid having recesses formed therein, a baffle arranged beneath the grid and slidable within the recesses, a handle carried by the grid and provided with a longitudinal slot, and an element secured to the baffle and slidable within the longitudinal slot. 125

4. In a stove of the character described,

an oven chamber, a burner chamber having means of communication with the lower portion of the oven chamber, a burner within the burner chamber, a grid arranged above the burner chamber and having supporting legs, a baffle arranged upon one side of the grid and having slidable connection therewith, said baffle embodying a heat resisting element, a handle secured to

the grid and having a longitudinal slot, and 10 an element connected to the baffle and slideable within the longitudinal slot of the handle and adapted to shift the baffle.
